United States Patent Office

Des. 188,956
Patented Oct. 4, 1960

188,956

FLASHLIGHT

Herman G. Graubner, New York, N.Y., assignor to
Union Carbide Corporation, a corporation of New
York

Filed Nov. 16, 1959, Ser. No. 58,367

Term of patent 14 years

(Cl. D48—24)

Fig. 1.

Fig. 2.

Fig. 1 is a perspective view of a flashlight, showing my new design.

Fig. 2 is a side elevational view of the flashlight shown in Fig. 1.

Fig. 3 is an elevational view thereof as seen from the left of Fig. 2.

Fig. 4 is an elevational view thereof as seen from the right of Fig. 2.

The dominant features of my design reside in those portions of the accompanying drawing shown in solid lines.

I claim:

The ornamental design for a flashlight, as shown and described.
